12 Claims

This invention relates to a low pressure plasma noise generator, and more particularly to such a generator that produces a continuous spectrum of noise over a relatively broad frequency range and at a power level that is uncommonly high for devices of this type.

Noise sources are useful in performing certain tests on electromagnetic wave receiving equipment and also are useful in a military environment for various countermeasures purposes. Noise generators that presently are commonly employed include resistors generating thermal noise when heated to elevated temperatures, gas discharges in fluorescent tubes, and various types of microwave tubes that operate saturated on their inherent noise. The first two of the above-mentioned noise sources are limited in their power outputs, their maximum power outputs being around 10 db and 20 db, respectively, these being less than one-half the 50 db power level obtainable from the device of this invention. The third-mentioned noise source is comparatively expensive to build and ordinarily is rather limited in its frequency range.

It therefore is an object of this invention to provide a relatively high power noise source that produces a continuous output over a relatively wide frequency range.

A further object of this invention is to provide a relatively inexpensive noise source having a controllable high output power.

A further object of this invention is to provide a plasma filled discharge tube that produces a noise signal over a continuous, relatively wide frequency range and at a high power level that may be varied by an electrical control signal.

Another object of this invention is to provide a low pressure gas discharge tube operating under such conditions that it produces bands of relatively high power non-coherent noise in both of two different wave polarizations, the bands of noise of the two polarizations being combined by suitable transmission line apparatus to produce a continuous broad frequency spectrum of relatively high power noise.

These and other objects and advantages of the invention, which will become obvious from reading the specification and claims below, are achieved on one illustrated embodiment of the invention by providing first and second sections of rectangular waveguide each of which support electromagnetic waves only in the dominant TE_{10} waveguide mode. These waveguide sections are disposed adjacent each other with their broad walls perpendicular to each other. An elongated gas discharge tube filled with a noble gas such as neon at a low pressure of the order of 10 microns extends transversely through both waveguides, extending between the broad walls of one waveguide and between the narrow walls of the other one. When the discharge is established within the gas tube, relatively incoherent oscillations of electromagnetic waves are established in each of the waveguides. Oscillations in the two waveguides are the same to the extent that they both have a comb-like characteristic as a function of frequency, but they differ to the extent that the frequencies of the oscillations are different in the two waveguides. The oscillations in one waveguide have maxima that are regularly spaced throughout a wide frequency spectrum, and the oscillations in the other waveguide also have

2

maxima that are regularly spaced throughout the same frequency range, but these maxima fall midway between frequencies of the maxima of oscillations in the first waveguide. By combining the outputs of both waveguides a relatively high level, continuous broad frequency spectrum of noise will be available at an output terminal. These results may be obtained without the use of a magnetizing field in the discharge. By applying a unidirectional magnetic field of variable strength, the oscillations may be set to a certain magnitude, or may be modulated in amplitude.

The present invention will be described by referring to the accompanying drawings wherein:

FIG. 1 is an illustration, partly in schematic form, of one embodiment of the present invention;

FIG. 2 is a graph showing several curves that are used in explaining the operation of the apparatus illustrated in FIG. 1; and

FIGS. 3 and 4 are simplified illustrations of further embodiments of the present invention.

Referring now in detail to the drawings, the embodiment of the invention illustrated in FIG. 1 is comprised of first and second sections of hollow rectangular waveguides 11 and 12, each adapted to propagate electromagnetic waves in the dominant TE_{10} mode, and both having approximately the same physical dimensions so that they propagate waves within the same frequency range. As illustrated, waveguides 11 and 12 are positioned with their respective broad walls orthogonal to each other so that the directions of the electric fields of the dominant modes in the two waveguides also are orthogonal. Waveguides 11 and 12 each are provided with a termination 13, 14, respectively, at one end, and the waveguide-to-coaxial line couplers 16 and 17 couple electromagnetic waves from the other ends of the waveguides.

An elongated low pressure gas discharge tube 20 extends transversely through both waveguides 11 and 12. The longitudinal axis of tube 20 is perpendicular to the direction of polarization of the electric field E_1 of TE_{10} mode electromagnetic waves in waveguide 11, and parallel to the direction of polarization of the electric field E_2 of TE_{10} mode waves in waveguide 12. Gas discharge tube 20 includes at one end an electron emissive cathode 21, such as an oxide coated nickel mesh cathode, and an electron collecting anode electrode 22 is positioned at the opposite end. Discharge tube 20 is made of a non-conducting material such as glass or quartz, and in one embodiment of the invention, had an inner diameter of 9 millimeters and a length of 3 feet, although the length is not critical. Tube 20 is filled with an ionizable gas at a low pressure. I have successfully used neon gas at pressures ranging between 10 and 50 microns. I also have successfully used other noble gases such as helium, argon, and krypton at pressures of approximately 80, 5, and 1 microns, respectively. Mixtures of the above gases may be employed as the ionizable medium, if desired. Oscillations in mercury and xenon gases were of too small a magnitude to be of practical utility as a noise source. Solenoids 23, 24 and 25 may be disposed about discharge tube 20 in the region of waveguides 11 and 12 to establish, when desired, a longitudinally directed unidirectional magnetic field through the central portion of the tube.

Cathode 21 is heated by means of a current from battery 26 and the potential between cathode 21 and anode 22, which was 1000 volts in one operating embodiment of the invention, is established by battery 27. A discharge is initiated within tube 20 by means of starting pulser 28, and the discharge is stabilized by means of a resistor 29 of several hundred ohms in the biasing circuit. I have successfully operated the discharge tube with a discharge current of approximately one-quarter ampere, although this value is not critical.

As will be explained in more detail below, electromagnetic waves are generated in gas tube 20 and propagate within the respective waveguides 21 and 22. The waves are coupled from the respective waveguides through the waveguide to coaxial transmission line couplers 16 and 17 and are coupled through suitable transmission lines 30 and 31 to a T-junction 33. Variable attenuators 36 and 37 are disposed in the lines 30 and 31 to equalize the power level of the two inputs to T-junction 33. Junction 33 combines the two input signals thereto, and the combined signal is coupled through isolator 38 to a suitable output terminal. It should be understood that other appropriate means may be employed for coupling the electromagnetic waves from the waveguide sections 11 and 12. These other means may employ coaxial or rectangular waveguide transmission lines and may include different types of combining networks.

Upon the establishment of the discharge within discharge tube 20 and the ionization of the gas contained therein due to the collision of the electrons in the electron stream with the gas atoms, well-defined relatively wide bands of noncoherent oscillations at regularly-spaced frequency intervals are set up in each one of the waveguides 11 and 12. The oscillations in each waveguide have a comb-like characteristic as a function of frequency, and the maxima of the various oscillatory bands are not the same in the two waveguides, but rather, the maxima of the oscillatory bands in one waveguide fall intermediate the maxima of the oscillatory bands in the other waveguide. This is illustrated in FIG. 2, wherein the curve designated $E_{\perp}$ represents the type of response detected in waveguide 11 wherein the axis of discharge tube 20 is perpendicular to the direction of the electric field vector E_1 , and the curve designated $E_{\parallel}$ represents the type of response detected in waveguide 12 wherein the axis of discharge tube 20 is parallel to the electric field vector E_2 . The maxima of each of the curves are regularly occurring throughout the frequency spectrum and have a separation of approximately 310 megacycles per second when neon gas at a pressure of approximately 20 microns is used. When argon gas was used, the frequency separation between the maxima was approximately 250 megacycles per second. After the signals E_1 and E_2 from waveguides 11 and 12 have been combined in T-junction 33, the combined signal will be a continuous, relatively constant magnitude and relatively incoherent noise signal that is coupled to the output terminal. As may be seen from FIG. 2, the bandwidth of the combined output signal extends approximately from 2 gigacycles (10^9 cycles) per second to 4 gigacycles per second. The bandwidth of the microwave circuitry employed will of course affect the bandwidth of the output signal. Ridged waveguides may be used for the waveguides 11 and 12 in order to obtain broad bandwidths in the microwave circuitry.

I have observed that the spacing between adjacent maxima on each curve decreases as the internal diameter of the discharge tube 20 increases. Therefore, by choosing the correct diameter for discharge tube 20, the maxima of the two curves $E_{\perp}$ and $E_{\parallel}$ may be adjusted to assure that the combined curves produce the desired continuous, relatively flat response which may be used as a broadband noise signal.

The magnitude of the combined output signal was found to be unexpectedly high for devices of this type, being of the order of 10^{-10} or 10^{-9} watts per megacycle per second, which is approximately 30 db or 40 db higher than that provided by commercially available standard noise tubes operating in the microwave frequency range.

I am at present unable to fully explain the reasons for the types of oscillations detected in the waveguides 11 and 12, and their behavior cannot be explained by existing theory and observations of resonant phenomena such as the Tonks-Dattner resonances that are reported, for example, in Physical Review Letters, 11, 183, 1963 by J.

C. Nickel, J. V. Parker, R. W. Gould. I have obtained noise outputs that represent noise figures greater than 50 db, and this magnitude of output is too great to be accounted for by single particle electron emission from the plasma. As used above, the term noise figure is a relative figure based on the noise output of a gas discharge tube at room temperature as the reference. Although the exact mechanism by which the oscillatory signals are generated is not known, it is believed that they are correlated with irregular current bursts in the discharge.

In operating embodiments of the invention the percent ionization of the gases within the discharge tube 20 ranged between .01 percent and .1 percent. Although the electrons in this type of discharge are not in thermal equilibrium, a measure of electron temperature that was made within the operating discharge tube indicated a mean electron temperature of approximately 8 to 10 electron volts. These electron temperatures are to be compared with the mean electron temperature of approximately 3.5 electron volts that was measured when the different Tonks-Dattner resonances were observed, these Tonks-Dattner resonances being of a very much lower magnitude of approximately 10^{-13} watts per megacycle per second.

The root means square plasma frequency was approximately at the center of the emitted band of frequencies. For radiation from 2-4 gigacycles per second this represents a mean electron density of approximately 10^{11} electrons per cubic centimeter, although the electron density may vary within the approximate range of 10^{10} to 10^{12} electrons per cubic centimeter. In operating embodiments of this invention I have found that the frequencies of the bands of oscillations varied but slightly with changes in the electron density, the frequency of the maxima shifting by only 3 percent when the electron density was doubled. Changes in electron density did, however, have some effect on the amplitudes of the oscillatory bands. As the electron density was increased, the amplitudes of the higher frequency oscillatory bands increased while the amplitudes of the lower frequency oscillatory bands were diminished.

Further, changes in the gas pressure within tube 20 has negligible effect on the frequencies of oscillations so long as the pressures of helium, neon, argon, and krypton were below approximately 100, 50, 5, and 1 microns, respectively.

All of the results and effects that have been discussed above are obtainable without a magnetizing field being applied to the ionized gas within discharge tube 20, and it is possible that a fully operable noise source may be constructed without the use of a magnetizing field. I have found, however, that when a unidirectional magnetic field is applied along the longitudinal axis of discharge tube 20 by the solenoids 23, 24, and 25, the frequencies of the oscillations are not affected, but their magnitudes are affected. Beginning with a low magnetic field strength of several gauss, and with the discharge tube filled with neon gas at a pressure of approximately 20 microns, the magnitude of the envelope of the curves of FIG. 2 will increase to a maximum value at a field strength of approximately 4 gauss, and then will decrease as the magnetic field strength is further increased. Oscillations were no longer detectable when the applied magnetic field was in the range between 20 and 30 gauss. This affords the possibility of controlling the magnitude of the noise output to a desired value, and also affords the possibility of modulating the amplitude of the output noise signal by means of an electrical modulating signal applied to the solenoids.

Another embodiment of the present invention is illustrated in FIG. 3 in which the gas discharge tube 20 and its associated discharge circuitry, as well as the noise signal combining circuitry, are substantially identical to those illustrated in FIG. 1 and are designated by the same reference numerals. In FIG. 3, discharge tube 20 extends

transversely through the vertical walls 41-42 of square hollow uniconductor waveguide section 43. Square waveguide section 43 is dimensioned to support electromagnetic waves in orthogonally disposed dominant TE_{10} modes. When the discharge is initiated within discharge tube 20, oscillations of both of the types illustrated in FIG. 2 will be set up in square waveguide section 43. The component $E_{\perp}$ will be coupled from waveguide section 43 by coaxial coupler 16, and the component $E_{\parallel}$ will be coupled from waveguide section 43 by coaxial coupler 17. These two components will be balanced in magnitude by the attenuators 36 and 37 and will be combined in T-junction 33 to form the continuous, high power, broadband noncoherent noise signal that is coupled through isolator 38 to the output terminal. The section of square waveguide 43 will be closed at its left end by a suitable termination, which is not illustrated.

Another embodiment of this invention is illustrated in FIG. 4 in which the gas discharge tube 60 includes the conventional electron emissive cathode 61 and collector anode 62, which together with voltage sources 26 and 27 and resistor 29 establish a discharge within tube 60. Discharge tube 60 is filled with one of the above-identified ionizable gases under the appropriate conditions to establish the same type of discharge and ionization condition as described above. In this embodiment of the invention, gas discharge tube 60 is tapered in diameter throughout its length so as to form a conically-shaped envelope which is made of glass, quartz, or other suitable material.

As mentioned previously, I have determined that the various frequencies at which oscillations were detected is a function of the diameter of the gas discharge tube. Therefore, by varying the diameter of tube 60 throughout an appropriate range of diameters, relatively high power oscillations may be obtained throughout a substantially continuous broad range of frequencies, thereby avoiding the comb-like characteristic that is obtained from a gas tube of constant diameter traversing a single hollow waveguide. Further, there is no need in this embodiment of the invention for associated transmission line circuitry to combine two different oscillatory signals as was necessary in the embodiments of FIGS. 1 and 3.

In this embodiment of the invention, the relatively continuous spectrum of oscillation is coupled out to coaxial transmission line terminal 50 by means of a TEM mode transmission line arrangement comprised of a narrow thin conductive member 65 which is spiraled about the envelope of gas discharge tube 60 and makes conductive contact with the inner conductor 66 of coaxial transmission line terminal 50. A conically-shaped conductive member 68 is disposed in spaced relationship about gas discharge tube 60 and acts as the ground conductor of the TEM mode transmission line arrangement. Means are provided at the right end of the conically-shaped conductive member 68 to suitably terminate that end of the device.

In the operation of the device of FIG. 4, the parameters of the gas discharge tube 60 and its exciting circuitry are adjusted to establish the previously-mentioned conditions within the tube, and because of the varying diameter of tube 60 oscillations of relatively incoherent electromagnetic waves will be produced throughout a substantially continuously frequency spectrum and these oscillations are coupled to the TEM mode transmission line arrangement comprised of strip conductor 65, ground conductor 68 and will propagate to the output terminal 50.

It should be understood that gas discharge tube 60 may be reduced in diameter throughout its length by a series of successively spaced discrete steps rather than being uniformly tapered as illustrated in FIG. 4.

Any of the devices illustrated in FIGS. 1, 3 or 4 also may be utilized as a signal source for supplying oscillations over a relatively narrow frequency range by providing frequency selective filtering means at the output 75

of the waveguide sections, and by omitting the combining T-junctions in the embodiments of FIGS. 1 and 3. With this type of arrangement, any desired one of the various maxima of oscillations may be selected for transmission to a suitable utilization means.

5 While the invention has been described in its preferred embodiments, it is to be understood that the words which have been used are words of description rather than limitation and that changes within the purview of the appended claims may be made without departing from the true scope and spirit of the invention in its broader aspects.

What is claimed is:

1. A plasma source of oscillations comprising:
an elongated gas container having a transverse dimension which varies along its length for confining a gas under pressure,
an ionizable gas within said container at a pressure below approximately 100 microns,
means for ionizing said gas to the extent of between .01 to .1 percent and to produce an electron density within said container ranging between approximately 10^{10} and 10^{12} electrons per cubic centimeter,
the mean energy of electrons within the plasma, as determined by electron temperature measurements, ranging between approximately 8-10 electron volts,
said ionized gas being characterized by generating oscillations of electromagnetic waves over a relatively wide frequency range, and
electromagnetic waves supporting means disposed in wave coupling relationship with said ionizable gas for coupling to said oscillations.

2. The combination claimed in claim 1 and further including:
means for immersing said gas container in a magnetic field.

3. The combination claimed in claim 1 wherein said electromagnetic wave supporting means is comprised of TEM mode wave propagating means.

4. The combination claimed in claim 1 wherein the gas is selected from the group of noble gases that includes helium, neon, argon and krypton.

5. A plasma source of oscillations comprising:
a gas container for confining a gas under pressure,
an ionizable gas within said container, said gas being selected from the group of noble gases that includes helium, neon, argon and krypton maintained at a pressure below a maximum pressure of approximately 100, 50, 5, and 1 micron, respectively,
means for ionizing said gas to the extent of between .01 to .1 percent and to produce an electron density within said container ranging between approximately 10^{10} and 10^{12} electrons per cubic centimeter,
the mean energy of electrons within the plasma, as determined by electron temperature measurements ranging between approximately 8-10 electron volts, said ionized gas being characterized by generating oscillations of electromagnetic waves over a relatively wide frequency range, and

60 electromagnetic waves supporting means disposed in wave coupling relationship with said ionizable gas for coupling to said oscillations.

6. Apparatus for producing relatively high power, broadband, incoherent oscillations of electromagnetic waves, said apparatus comprising:

an elongated gas discharge tube comprised of a tube of dielectric material having an ionizable gas confined therein,
a section of hollow waveguide adapted to support orthogonally polarized oscillations of electromagnetic waves within a given frequency range,
said discharge tube extending transversely through said waveguide so that a discharge within said tube presents an ionized gas within the bounds of said waveguides, and

electromagnetic wave coupling means for coupling to electromagnetic waves in each of said two orthogonal polarizations within said waveguide.

7. A high power noise source comprising: first and second rectangular waveguides having broad and narrow walls and each adapted to propagate electromagnetic waves within a given frequency range in the dominant TE_{10} mode,

said waveguides being disposed adjacent each other with their respective broad walls orthogonal to each other,

an elongated gas discharge tube extending transversely between the narrow walls of the first waveguide and transversely between the broad walls of the second waveguide, and

means for extracting and combining electromagnetic waves from said two waveguides to produce a composite electromagnetic wave signal.

8. A high power noise source comprising: a gas discharge tube containing an ionizable gas at a pressure below approximately 100 microns,

means for establishing a discharge within said tube to ionize said gas to the extent between .01 to .1 percent,

said discharge tube, with the discharge established therein, generating electromagnetic waves that are supportable in two electromagnetic wave modes,

means disposed in electromagnetic wave coupling relationship with said discharge tube for supporting oscillations of said generated electromagnetic waves in each of said two modes,

the waves of said two modes being characterized by having different frequency contents, and

means for combining the waves of said two modes to produce a composite signal therefrom having the frequency content of both of said modes.

9. A high power noise source comprising: a gas discharge tube filled with an ionizable gas at a pressure below approximately 100 microns,

means for establishing a discharge of charged particles within said tube to ionize said gas to the extent from .01 to .1 percent,

said discharge tube, with the discharge established therein, generating electromagnetic waves hav-

ing components that are supportable in two orthogonal electromagnetic wave dominant modes,

electromagnetic wave structure adapted to support electromagnetic waves in said two modes,

said structure being disposed relative to said tube to receive from said tube electromagnetic waves in said two modes, and

means for extracting and combining from said structure electromagnetic waves in said two modes.

10. The combination claimed in claim 9 and further including:

means for establishing a unidirectional magnetic field directed along said discharge tube.

11. The combination claimed in claim 9 wherein the gas is selected from the group of noble gases that includes helium, neon, argon and krypton.

12. The combination claimed in claim 11 wherein the gas within said container is one of the named gases at a pressure of 100, 50, 5 and 1 micron, respectively.
